UNITED STATES PATENT OFFICE.

OSKAR K. KLEIN, OF CLEVELAND, OHIO.

PERMUTATION-LOCK FOR ELECTRIC SWITCHES.

1,314,749.

Specification of Letters Patent.

Patented Sept. 2, 1919.

Application filed December 31, 1917. Serial No 209,746.

To all whom it may concern:

Be it known that I, OSKAR K. KLEIN, a citizen of the United States, and resident of Cleveland, in the county of Cuyahoga and State of Ohio, have invented certain new and useful Improvements in Permutation-Locks for Electric Switches, of which I hereby declare the following to be a full, clear, and exact description, such as will enable others skilled in the art to which it appertains to make and use the same.

The objects of the invention are to provide a combination lock and casing for the electric starting switch of an automobile.

The invention also includes means for locking the retaining bolt for the casing so that it can not be removed from the machine until the combination is set thus protecting the machine from being stolen or operated by irresponsible persons.

The invention comprises a casing provided with a depressible inner plate, which contains a series of keyholes, and which is employed in connection with a corresponding series of rotatable keys each having a web which will pass through its similarly shaped keyhole when in the properly adjusted position but will prevent the movement of the depressible plate until the exact combination of all the keyholes and keys has been formed.

It includes a depressible and rotatable key for operating the electric switch which is normally held out of engagement therewith and is prevented from rotation until the proper position therefor has been obtained.

It also includes a retaining bolt, or screw for the casing, the movements of which are also controlled by the position of the depressible plate which contains the combination key holes.

The invention is illustrated by means of the accompanying drawings and is herein-after further described, and specifically claimed.

In the accompanying drawings Figure 1 is front elevation of the device; Fig. 2 is a side elevation thereof; Fig. 3 is an enlarged front elevation of the casing; Fig. 4 is a transverse section thereof; Fig. 5 is a bottom view.

In these views A is the casing which is detachably secured to the switch box B by means of the clamping bar C and a screw threaded bolt D which enters a screw threaded opening E in the switch box.

Within the casing is shown the depressible plate F which is provided with keyholes G G through which the webs H H of a series of keys I I are adapted to pass only when the keys are turned to the prescribed combination.

To increase the difficulty in releasing the plate F, a number of false key holes J J are provided in the depressible plate and a corresponding number of numerals or a greater number are shown at K upon the outside of the casing only one in each series of which corresponds with the right key hole.

The switch member L is provided with spaced openings M M and a depressible and rotatable key N is mounted in the casing and is provided with lugs O O which when the key is depressed engage the openings M and by rotating the key the switch can be turned.

In Fig. 4 the plate F which contains the key holes J J is shown in raised and locked position and the central key N is rotatable in the casing and in the plate F but cannot be depressed or lowered until the said plate F is unlocked or released. A central key or main pin N which is raised out of engagement with the switch member L in said Fig. 4 has its lug T located at the upper face of the casing and adapted through the rotation of the pin N to be carried into and out of register with the notch V. When the plate F is unlocked and released by a proper operation of the keys I and the lug T turned into register with the notch V, the compressed spring P, which is interposed between the casing and the plate F will expand and force the plate F and the central key N downwardly and carry the lugs or projections O of the flange or head Q into engagement with the recesses M of the switch member L. This will permit the switch member to be operated by the central pin or key. The central pin or key is adapted to be drawn upward out of engagement with the switch member L and it is adapted to carry the plate F to the position shown in Fig. 4 of the drawing.

The pin N is then adapted to be partially rotated to carry the lug T out of register with the notch V and the keys I may then be rotated to carry the webs H out of register with the key holes of the plate F which will be locked against downward movement by the said webs or projections H.

The locking bolt D can only be turned

to insert or release the same when the key hole plate is lowered, as when the said plate is raised a web R upon the side of the bolt on screw D enters a hole S in the said plate 5 and the screw can not be turned to release it.

The key N is normally held out of engagement with the switch by means of a pin T which can be released through the slot V in the casing; also it will be seen that the 10 key N cannot be rotated until the lug T is raised above slot V, and hence cannot be employed to rotate the switch until the plate is lowered and the spring P on which it rests and which prevents its movement 15 is expanded.

Having described the invention what I claim as new and desire to secure by Letters Patent is—

1. A lock of the class described including a casing, a plate vertically movable in the casing, a key mounted for rotary movement in the casing and in the said plate and provided with means for engaging the casing or holding the plate and the said 20 key in an elevated position; a spring mounted on the said key and arranged to urge the plate and the key downwardly or inwardly when the said key and plate are free 25

to move in such direction, and a plurality of locking keys mounted on the casing and provided with means for engaging the plate 30 for locking the same in an elevated position.

2. A lock of the class described including a casing, a plate vertically movable in the 35 casing and provided with key holes, a key mounted for rotary movement in the casing and in the said plate and provided with means for engaging the casing for holding the plate and the said key in an elevated 40 position; a spring mounted on the said key and arranged to urge the plate and the key downwardly or inwardly when the said key and plate are free to move in such direction, and a plurality of locking keys 45 extending through the key holes and forming guides for the vertically movable plate and provided with means for engaging the same to lock the said plate in an elevated position. 50

In testimony whereof, I hereunto set my hand.

OSKAR K. KLEIN.

In presence of—
CHAS. F. SNIPE.
